[57] ABSTRACT

An indicator system with signal indicators arranged in lines and columns, each indicator having a stepping motor and a release relay and being interconnected through control switches to require a minimum of interconnecting wiring. A switch means is provided in each signal indicator, and is actuated by the release relay.

INDICATOR SYSTEM WITH SIGNAL INDICATORS

This invention relates to an indicator system with signal indicators arranged in lines and columns. The signal indicators are each provided with a stepping motor having two conductors and which powers a rotary signal indicator. These indicators are in the form of an interchangeable mechanical unit. A known signal indicator is disclosed, for example, in Swiss Pat No. 386,297. In such a known system, only signal indicators relating to a particular line receive power supply which feeds the signal indicators of a plurality of lines via a column circuit with a common ground. This is achieved by connecting one conductor of the stepping motor of all signal indicators to the common ground and to connect the other conductor of each unit with one respective switch which connects it to its respective column circuit. The switches mentioned, relating to a line of signal indicators, will be operated by common control devices and powered by a power supply, so that a line of signal indicators can be adjusted through currents fed through the respective column circuits.

The switch means relating to each signal indicator is in the form of a relay contact. Each line must be equipped with a number of relays, depending upon the maximum number of contacts per relay that can be utilized. The space requirement for the relays is usually the source of a troublesome problem. The relays can be located so as to provide easy access and maintenance, but in that case the wiring to the relays and relay contacts extending to the signal indicators, are usually required to be long and extensive. If the wiring is to be made less extensive, the result will of necessity be an arrangement of the relays in a manner or disposition in which ready access and maintenance are difficult.

To avoid the need for a multitude of contacts, solutions have been found in the prior art, as for example in Swiss Pat. No. 514,210, where only one or two contacts are used, in addition to rectifiers. The prior art shows that contacts, moreover can be replaced by thyristors, where the space and placement requirement is insignificant. Such designs, however, have the disadvantage that feeder lines for lines and columns which are not operative may be powered by operating voltages if maintenance is required. This can lead to major complications and damage if during maintenance operations, shorts between wires and frame occur while other parts of the system are operating; thus the damage can be far greater in such an arrangement than in a system where each signal indicator is provided with its respective relay contact.

It is the object of the present invention to provide an indicator system retaining the advantages which are offered by placing switch means for operating a signal indicator into one column circuit; and reducing the extent of wiring with a consequent reduction in the total wiring cost. The invention relates to a system which is characterized by placing the switch means into each signal indicator.

In systems with signal indicators provided with a locking device and a release relay or a release magnet, very advantageous versions of the invention are feasible. In one of these versions, the release relay is used for operating the switch means, therefore, no separate coil is required. In others it is possible to avoid need for separate wiring to operate the switch means.

Having reference to the accompanying drawings:

FIG. 1 shows a wiring diagram portion of an indicator system. The signal indicators are arranged and shown by way of illustration in three lines and in three columns, but this is not by way of limitation. Only one of the signal indicators is shown in detail, the others are simplified.

FIGS. 2 to 7 show schematics of other signal indicator designs.

FIG. 8 is a perspective representation of a switching relay which will operate in the complete signal indicator a locking device of the signal carrier as well as the switch which will actuate the stepping motor.

The nine signal indicators ZM shown schematically in FIG. 1 are interchangeable mechanical units of identical design. The signal indicator shown in the upper left discloses schematically more detail than is shown for the others. Each signal indicator ZM is provided with a stepping motor with a coil M having two conductors and a rotor A with a permanent magnet. This

motor will make half a turn if coil M is energized with impulses of alternating polarity and will drive a signal carrier ZT rotating around shaft X via a gear transmission. This signal indicator, of which merely one disc is shown, preferably consists of the ordinary drum type containing the signals or signs to be displayed. With each half turn of the stepping motor one of the signals or signs will be turned and another signal will be displayed. On the disc shown of signal indicator ZT, a pin B is disposed in a manner that its rotary path will interfere with latch SH. Therefore, the signal indicator has a locked position preventing further rotation. Further rotation only can occur when latch SH will be moved out of the path of movement of pin B through excitation of release relay F which, in turn, is provided with

two conductors. By means of this locking and release device, a signal indicator in an unknown arbitrary position can be moved back by a control device to an initial known position, from where another desired position can be chosen by counting the number of impulses fed to the stepping motor.

One example of the release relays used in FIG. 1 is shown in FIG. 8. Such a relay is provided with a coil F, a yoke 2 and mounted on it is armature 1 which will operate latch SH with its back portion 5. Latch SH also is pivotally supported but not shown here.

In FIG. 1 these details are shown simplified and the latch and armature are shown as one single piece. The front portion of the coil is provided with an extension 3 formed of a magnetic material. At the back portion of the yoke 2, which is the opposing magnetic pole, a similar extension 4 has been provided. Both extensions are designed with tabs 6 enclosing switch SK. The release relay, therefore, involves two magnetic circuits. The first circuit is formed through yoke 2 and armature 1. The second circuit is formed through extensions 3 and 4 and the switch means SK, therebetween. The two magnetic circuits serve to actuate latch SH and also the switch means SK. The magnetic conditions and the opposing force when the armature is attracted are chosen such that a threshold value exists. This means that under weak coil excitation, only switch means SK is closed and the armature remains in its open position; while under stronger excitation, the armature also will be attracted and will cause operation of latch SH.

One of the stepping motor conductors of each of the signal indicators ZM is interconnected and connected to one of the conductors of each release relay F and

then to a common conductor which is connected to ground. The other conductor of each stepping motor M is connected to the respective column circuit K1 - K3 via the respective switch means SK. The other conductor of each release relay F contained in a particular line of signal indicators are all connected to a common line circuit Z1 . . . Z3. Through this arrangement, all switch means SK of a particular line can be operated simultaneously.

A power supply SP energizing the entire system is provided with four conductors. The first conductor is connected to ground. Conductors +1 and -1 supply a relatively low voltage each being of equal potential, but opposite polarity. Conductor +2, however, is of a relatively high voltage. The voltages at conductor +1 and -1 are selected to be sufficient for the operation of the stepping motor M and for the operation of switch means SK, but inadequate for unlocking latch SH. Supplying a voltage +2 to the coil F causes operation of switch means SK and also the operation of latch SH and therefore the release of the signal carrier.

By means of the electronic switches K+ and K-, conductors +1 and -1 can be connected to the common column conductor KSS, which in turn can be connected selectively to the three column circuits K1 . . . K3 through switches KS1 . . . KS3. Choosing suitable combinations of these switches, therefore, selectively connects each column circuit to voltage +1 or -1.

The line circuits Z1 . . . Z3 are selectively connectable to voltage +1 through the electronic switches SS1 . . . SS3, also to voltage +2 through line switches FS1 . . . FS3. As explained previously, supplying voltage +1 to a line circuit will operate all switch means SK in signal indicators of a respective line; supplying the voltage +2 will actuate switch means SK and also the latch SH. Both of these operations consequently are controlled over the same conductor. Supplying different voltages will cause different currents in respective coils. A separate conductor for the operation of switch SK, therefore, can be omitted.

The control device ST is basically a programmer which consists of a fixed program and an additional changing program containing the information to be indicated, and will supply control criteria for the operation of the electronic switches explained before. Based on the position of these switches, the release relays of the new line will receive voltages through the line circuits Z on one hand and the stepping motors M adjusting to a new position through the column circuit K1 . . . K3 on the other hand, which they will in turn need to carry out the required function.

The nine signal indicators ZM shown in FIG. 1 will be adjusted per line by control device ST. Should a signal indicator be adjusted in a given line, for example, the second one, control device ST gives command to operate switch SS2 whereby supply voltage +1 will be connected to line circuit Z2. Consequently, a weak current will be passed through the release relay F of all signal indicators belonging to the second line. This will actuate switch means SK in all signal indicators of this second line; however, it leaves the latches in their locked positions. Each motor coil M of the second line is now connected to its respective column circuit K1 . . . K3 via switch means SK contained in each individual signal indicator.

Besides closing switch SS2, the control device ST also will close column switch KS1 . . . KS3 and there-

fore, prepare all signal indicators of the second line for receiving impulses. Subsequently, control device ST will alternately operate the switches K+ and K-. Alternating pulses from conductors +1 and -1 of power supply SP will be fed to the motors of respective signal indicators and from there to ground, over the three column circuits K1 . . . K3 and the switch means SK contained in signal indicators of the second line, whereby the motors will turn until pins B of all respective signal indicators will strike latches SH.

After this condition of an initial starting position has been reached, the control device ST will open switch SS2 and close FS2, whereby voltage +2 will be supplied to line circuit Z2. In coils F of the signal indicators of line 2, a larger current will flow now than previously, which not only will operate switch means SK, but also will bring latches SH into their releasing positions, so that the signal indicators can continue to turn.

During the period which follows, the control device ST will operate switches K+ and K- in the same fashion as before, but will operate column switch KS1 . . . KS3 in a way which depends on the signal or sign to be indicated in line 2. Each of these switches will be held in a closed position during a certain time, that is when motor M of the respective column and the second line will receive a certain number of pulses from switches K+ and K-, so that the signal indicator will turn to a signal or sign to be shown. Since ordinarily different signals will be exhibited by different signal indicators of a particular line, the time required when switches KS will be in their closed position, will also differ. Either all switches KS1 . . . KS3 can be closed simultaneously or all switches can be closed in such a way that the adjustment of a particular line of signal indicators will be completed simultaneously. After completing a certain setting, the control device will bring all electronic switches into the locked position and then it is ready for an adjustment of a new line.

FIGS. 2 . . . 7 show schematics of signal indicators which will be used in six alternate designs of indicator systems. Although the line and column circuitry in these examples does not match completely with that of FIG. 1, they are not explained here and not shown, because in the context of the explained first design all essential characteristics of these systems can be understood without further explanation. The differences of the signal indicators shown in FIGS. 2 . . . 7 versus those of FIGS. 1 and 8 are in alternate switch means connecting the stepping motors with their respective column circuits and way of operating these switch means.

In signal indicators as represented by FIGS. 2, 3 and 4, a relay A is used as switch means to connect column circuit K1 . . . K3 with the motor M of the respective column. A relay of any known design can be used. In the first two design examples, each relay is connected to a line circuit ZA which controls exclusively the relay of the signal indicators of a particular line. The signal indicator of FIG. 2 is not provided with a locking device and a release relay, while the signal indicator of FIG. 3 is provided with release relay F independent of relay A and fed independently by line circuit ZF. Here two lines circuits are required and the signal indicators require one more conductor each than those of FIG. 1.

In signal indicators of FIG. 4, however, only one line circuit Z and three conductors are required, despite the additional equipment of a separate relay and a release

relay. In this example, the relay A and release relay F are operated over the same line circuit Z. The selection of the device will be determined by the direction of current flow, as determined by a rectifier G1 in series with release relay F. The relay can be operated only if line circuit Z carries a positive voltage relative to ground at E. The relay A, however, closes switch means SK if a voltage of arbitrary polarity is being supplied. In a system with these signal indicators, therefore, the control device can operate the respective signal indicators of a line by supplying a voltage of negative polarity to the line circuit and hence will operate relay A only, but by supplying a positive voltage, it will operate relay A and relay F together.

The signal indicator as represented by FIG. 5 is provided with a release relay as shown in FIG. 8 and explained in the system of FIG. 1.

Switch means SK are designed similarly in that system. Below a certain threshold value of magnetic excitement of the release relay, only switch means SK will be operated, but when excitement above said threshold occurs, the latch will be operated over the same conductor. In contrast to FIG. 1, however, it is not the different currents caused by different voltages that will effect the different values, but rather voltages of different polarity. This will be achieved by positioning a rectifier G2 and resistor R1 parallel to each other in series to the release relay F. When supplying a positive voltage to line circuit Z, the resistor R1 is bypassed, and therefore, the current is large. A supply of a negative voltage creates a small current being only that passed through R1. The value of R1 is determined by the operating voltage, the threshold value of the latch and the switch SK, so that the larger current is adequate to unlatch and operate the motor while the smaller current just operates the motor.

FIGS. 6 and 7 shows designs of signal indicators where the switch means SK, connecting the motor to its respective column conductor, are replaced by one or two thyristors. These signal indicators again include a release relay F. Over the same conductor, which is line circuit Z, the latch can be operated. As well, the thyristor can be changed to its conductive condition. In one system as it is shown in FIG. 6, two thyristors T1, T2, are switched antiparallel. The thyristors are switched by an A.C. voltage supplied over line circuit Z.

To accomplish this inside the signal indicator, a transformer U is provided with its primary side parallel to coil F of the release relay. The capacitor C in series to the transformer coil prevents a flow of direct current. The transformer is provided with two secondary coils, the first in series with a resistor R2 between cathode and switching electrode of thyristor T1, while the secondary coil along with resistor R3 has the same effect on thyristor T2. If no A.C. voltage exists between line circuit Z and ground E, no current can flow. If an A.C. voltage, preferably in audible frequency range, is supplied, both thyristors will be constantly supplied with a switching voltage, so that between column circuit K and motor M, currents can flow in either direction. The release relay F of a line will be operated when a D.C. voltage will be supplied to the respective line circuit Z. Since the excitement in release relay is only adequate if the thyristor will be switching, the D.C. voltage has to be superimposed over the A.C. voltage. Basically coil F could be used as transformer.

The two-way thyristor ZT inserted as switching means into the signal indicator of FIG. 7 requires a positive voltage against ground at its switching electrode to permit currents to flow in either direction. This switching electrode is connected to line circuit Z over a resistor R4. Since the coil of release relay F is wired between line circuit and ground, no voltage is present between motor M, the connected electrode of the thyristor and the switching electrode, unless the line circuit is supplied with a voltage. This means that in this condition the thyristor is blocked for current flow in either direction. To operate the motors of a line of signal indicators between column circuit K, a positive voltage to the respective line circuit Z is required, whereby in each signal indicator of the respective line the switching electrode of the thyristor will become positive through resistor R4 and against motor M; thus the thyristor will switch or ignite and allow current flow in either direction. The value of resistors R4 are determined such that on one side the thyristors will respond when a voltage is supplied to line circuit Z, while the release relays which are also connected to the line circuit will not respond. On the other hand, the voltage required to operate the release relays is still an allowable current for the switching or ignition electrode of the thyristor. In this design, like that shown in FIGS. 1 and 8, the voltage level supplied to line circuit Z either can result in switching column circuits K and the motor or the latter including the release of the latch mechanism. To reduce the differential of the voltages required, a Zener diode in series with coil F of release relay F could be provided, which would have to be sized according to the coil.

The arrangement of switch means SK in the interchangeable mechanical units of signal indicators permits a minimum of wiring in an indicator system. A defect in a switch SK can only affect the respective signal indicator and, therefore, can be eliminated easily by exchanging the whole signal indicator. It is to be understood that the invention is not limited to the designs shown. Without leaving the idea of the invention, more solutions could be arranged by various combinations of possibilities shown in the examples. The invention also should not be limited to the application of stepping motors by movement through impulses of alternating polarity.

What is claimed is:

1. An indicator system comprising a plurality of interchangeable signal indicators each being placed in respective rows and columns and having a stepping motor with two conductors and a rotatable signal carrier mechanically driven by said stepping motor, and a mechanical stop for stopping said signal carrier in a defined position, and a release magnet for releasing said mechanical stop, a power supply for providing a common potential to one of the conductors of each stepping motor and to said release magnet and a predetermined voltage potential to a plurality of column conductors to which the other conductor of all signal indicators of the respective column can be connected, said power supply further adapted to supply a predetermined voltage potential to one side of each said release magnet of a selected row, a stepping motor switch means connecting each respective stepping motor to its respective column conductor, and a column control switch means interconnecting said power supply means to each respective column conductor, said stepping

motor switch means being disposed within each signal indicator and being adapted for actuation in response to certain energization of said release magnet.

2. An indicator system as claimed in claim 1 characterized in that said stepping motor switch means and said release magnet are designed with a threshold characteristic as to enable actuation of said stepping motor switch means at one potential of applied voltage, and actuation of both said stepping motor switch means and said release magnet at another potential of applied voltage.

3. An indicator system as claimed in claim 2 characterized in that said release magnet comprises a single magnetic coil and separate magnetic circuit for actuating said stepping motor switch means and said mechanical stop.

4. An indicator system as claimed in claim 3 comprising a resistor and a rectifier connected in parallel with each other and in series with the coil of said release magnet to produce different values of energizing current in response to the polarity of voltage applied thereto.

5. An indicator system as claimed in claim 3 wherein said stepping motor switch means comprise reed contacts.

6. An indicator system as claimed in claim 1 wherein said stepping motor switch means consist of thyristors.

7. An indicator system as claimed in claim 1 characterized in that said power supply is adapted to supply

impulses of alternating polarity to drive said stepping motor, said stepping motor switch means consisting of thyristors connected in anti-parallel.

8. An indicator system as claimed in claim 1 characterized in that said power supply is adapted to supply impulses of alternating polarity, said stepping motor switch means comprising a two way thyristor (triac).

9. An indicator system as claimed in claim 1 comprising a row conductor for each row of signal indicators, each signal indicator having first and second row switch means for each row, the first row switch means connecting the respective row conductor to a predetermined first voltage potential and the second row switch means connecting the respective row conductor to a

15 predetermined second voltage potential of said power supply, said release magnet being adapted to actuate only said stepping motor switch means upon actuation by said first voltage potential and being further adapted to actuate both the stepping motor switch means and 20 said release magnet upon actuation by said second voltage potential.

10. An indicator system as claimed in claim 9 wherein said stepping motor switch means and the release magnet are connected in a manner such that the 25 stepping motor switch means are actuated in response to energization of either polarity and the release magnet is actuated only in response to energization of a single polarity.
